UNITED STATES PATENT OFFICE.

JOHN PEMBERTON SNAPP, OF LIMESTONE, TENNESSEE.

GUIDE TOOL.

Application filed May 7, 1926. Serial No. 107,483.

The object of this invention is to provide means for holding and guiding the ends of a wire clamp adapted to pass around the sections of a pole, such as a telegraph or telephone pole, to be spliced,—thereby avoiding the necessity of holding the ends by hand while a vise or similar tool is being applied to the clamp.

A further object is to provide means for holding a threaded or plain and straight end of a wire clamp with reference to an eye member formed on the opposite end of the clamp, so that upon the application of a vise to the clamp the ends of the latter having sliding relation to each other will be brought to the position desired for securing the straight end in the eye member, by bending over said straight end, or otherwise securing it.

20 A further object is to produce a guide tool comprising a pair of pivotally mounted jaws each having a channel extending transversely thereof, the channels cooperating to form a bore thru which the straight end of the wire clamp loosely projects.

A further object is to provide a third jaw, pivotally mounted, and carrying a spring held plunger adapted to pass thru the eye and enter the end of the bore for holding 20 the elements in registration, the eye being engaged by the third jaw and the plunger receding as the straight end of the wire clamp is carried by the vise thru the eye, the third jaw also receding upon further movement.

With the foregoing and other objects in view, the invention consists in the novel construction and arrangement of elements described, illustrated and claimed, it being understood that modifications may be made 40 within the scope of the claims without departing from the spirit of the invention.

In the drawings forming part of this application—

45 Fig. 1 is a view of the device in elevation, the third jaw and handle therefor appearing in full line and in dotted line position;

Fig. 2 is a view in elevation, from another angle;

50 Fig. 3 is a view in end elevation, the view also constituting a top plan when the tool is in vertical position;

Fig. 4 is a detail view in elevation and section, showing especially the relation of 55 the third jaw to one of the other jaws, and the manner of mounting the plunger; and

Fig. 5 is a detail view of a loop clamp.

In carrying out the invention, I employ a pincer-like tool comprising jaws 10 each provided with a channel or groove 11 extending transversely thereof near the rounded end 12, the groove being on the inner side, and the two grooves cooperating to form a bore thru which the straight end 13 of a wire clamp is adapted to pass, this clamp being in the form of a loop member and adapted to surround the two pole sections. The opposite end 14 of the clamp includes an eye member 15, and the elements 13 and 15 are to be held by the tool in the position of Figs. 1 and 4, so that the workman in applying a vise to the clamp will not be obliged to reach around the pole in order to see that the ends are properly cooperating,—it being necessary in purely hand operation to hold 75 the end manually.

The tool when thus applied, will assume a vertical or suspended position, if the clamp is applied a considerable distance above the surface of the ground, but it is not necessary that the handle portions be in the position indicated, as the tool will serve the function equally well if in a horizontal position, or in fact at any angle.

80 The jaws 10 are pivotally connected by bolt or rivet 17, and a third jaw 18 is mounted on one of the jaws first named or on the shank portion thereof, by means of pivot member 19. A spring 20 connects the handle of the third jaw with the handle of either of the other jaws, this being a tension spring and normally holding the third jaw in the position of Figs. 1 and 4.

85 A strap or loop member 25 is pivotally connected at 26 with handle 23, and is adapted to engage the handle 21 of the other jaw 10. A spring 27, of the form shown in Fig. 2 is mounted on handle 24, and includes an offset portion adapted to engage and retain the U-portion of strap 25, for the purpose of 90 retaining the two jaws 10 in cooperating relation in order to form the bore for the straight end 13 of the wire clamp.

An important feature of the construction 105 is the mounting of a plunger 30 in the third jaw 18, this plunger extending transversely of the end of the jaw and being held in the position of Fig. 4 by a spring 31 mounted in recess 32 in the jaw. The end of plunger 30 carries a head 33, and the opposite end 110 is adapted to pass thru eye member 15 of the wire clamp and to enter the end of the

bore formed by the grooves 11 in the jaws 10. This retains the elements in proper relation, so that the straight end 13 of the clamp will be in position to pass thru the eye 15. The end 34 of jaw 18 has the special form shown in Fig. 4, and is adapted to partly enter the opening formed by the eye, this portion 34 being of annular form and having a curved or slightly reduced portion 10 serving the purpose intended, that is, effecting close cooperation with the eye member.

It will be understood that the loop clamp formed of wire and adapted to surround the pole sections to be spliced is to be tightened 15 by a vise-like tool, and the end 13 will be forced into contact with the plunger, the latter will recede under the action of its spring, and the end 13 will pass thru eye 15. Upon further movement the jaw 18 will 20 recede and move about pivot 19 and against the action of light spring 20. The guide tool has now served its purpose, and the end 13 of the wire clamp is to be bent over or 25 clinched with reference to the eye 15, or otherwise secured, it being assumed that the clamp is still being held by the vise, not shown in this case, but employed for applying the clamp to the pole sections.

Having described the invention what is 30 claimed is:—

1. In a device of the class described, a

pair of jaws pivotally connected and channeled transversely, the channels being opposite each other, a third jaw movable about a pivotal point at an angle to the axis of movement of the jaws first named, and an element mounted in the third jaw and movable thru this jaw in alinement with a bore formed by the channeled portions.

2. In a device of the class described, a pair of jaws pivotally connected and channeled transversely, the channels being opposite each other, a third jaw movable about a pivotal point at an angle to the axis of movement of the jaws first named, and a 40 spring-held element mounted in the third jaw and extending therethru in alinement with a bore formed by the channeled portions.

3. In a device of the class described, a pair of jaws pivotally connected and channeled transversely, the channels being opposite each other, a third jaw movable about a pivotal point at an angle to the axis of movement of the jaws first named, the third jaw having a transverse bore therein and a chamber communicating with the bore, a plunger extending thru the bore and chamber, and a spring for normally forcing the plunger toward the jaws first named.

In testimony whereof I affix my signature.
JOHN PEMBERTON SNAPP.
